UNITED STATES PATENT OFFICE

GEORGE HENRY ELWELL, OF NEW HAVEN, CONNECTICUT, ASSIGNOR TO THE GREIST MANUFACTURING COMPANY, A CORPORATION OF CONNECTICUT

ELECTRIC-LAMP SOCKET

Application filed October 10, 1927. Serial No. 225,191.

The invention relates to improvements in electric lamp sockets and especially to the manner in which the screw-shell contact member is secured to the body of insulation. In the manufacture of the screw-shell contact member it is customary to form it up into a cup shape and then to cut out a substantial portion of the bottom of the cup to provide an open space for the center contact presented within the shell by the usual washer of insulation lying between the screw-shell and the body of insulation. Not only is the center opening thus provided in the screw-shell contact for the reason stated, but the opening is usually diametrically enlarged by transverse extensions reaching entirely across the bottom and extending a substantial distance into opposite portions of the adjacent cylindrical wall of the shell. These extensions provide clearance for binding-posts in a manner well-known to the art. The metal bottom portion thus cut from the screw-shell becomes waste material and the shell is assembled to the body of insulation by means such as screws extending axially through the body and washer of insulation and through a remaining portion of the screw-shell bottom to terminate in threaded bores in the anchorage of one of the binding posts. It is therefore one of the objects of this invention to provide a screw-shell contact having integral arms formed from the metal ordinarily discarded as aforesaid, one of these arms providing a binding-post for the screw-shell contact while both of the arms provide an important part of the assembling means of the shell to the body. Other objects will appear as the invention is described.

The following is the description of an embodiment of the invention, the construction of which may be varied within the scope of what is hereinafter claimed, reference being had to the accompanying drawing (one sheet) in which Figure 1 is an upright elevation of an improved lamp socket, the socket casing not being illustrated; Figure 2 is an upright elevation of the same socket, but in a different rotary position; Figure 3 is a cross-section at the dotted line "A—A" in Figure 1; and Figure 4 is a detail perspective view.

Similar parts are therein similarly numbered. The screw-shell contact 1 is provided with integral arms 2 and 3 made from parallel strips partially cut from the metal bottom of the cupped shell and bent to extend axially along the periphery of the body of insulation 4. The washer 5, also of insulation material, may be provided with notches (not specifically illustrated) in which arms 2 and 3 may lie to maintain the washer in a positive relative rotary position thereto and hence to the lamp socket. The body of insulation 4 may be provided with axial grooves (not specifically illustrated) in its cylindrical surface to accommodate the arms 2 and 3 throughout their length within the periphery of that body. Indentations 6 and 7 presenting locking shoulders 8 and 9, respectively, are provided in the periphery of the body 4 to accommodate the off-set terminals 10 and 11 of the arms, each of these terminals being provided with screw-holes to receive, as illustrated by Figure 2, the screw 12 extending through the body 4 as illustrated more particularly by dotted lines in Figures 1 and 3, the threaded nut 13 permitting the tightening of the screw to bind the arms to the body with their off-set terminals locked behind their respective shoulders. When neither of the arms 2 and 3 are to be utilized as a binding post this screw 12 may be dispensed with, if desired; for the off-set terminals 10 and 11 having snapped into their respective locking indentations 6 and 7 the screw-shell contact may be sufficiently held thereby especially when the insulation lining (not illustrated) is made to fit snugly, as is customary, over that portion of the body 4. The arm 2 being selected as the screw-shell binding post, an axially directed bore 14, as best illustrated by Figure 2, in the body 4 provides a convenient passage from the capped end 15 of the socket for the circuit wire (not illustrated) connective, under the head of the screw 12, to that arm. The body 4 is provided with a cavity to accommodate an electric switch of any adaptable type, and leading from such cavity is a bore 16 extending axially farther into the body 4. A smaller bore 17 concentric with and continuous of the bore 16 terminates with

an opening in the capped end 15 of the lamp socket axis. A threaded and flanged sleeve 18 rests within bore 17 with its flange within bore 16, a bent side extension 19 of the flange 5 provided with one of the contact points for circuit closing engagement by a switch element, the other contact point being presented by a washer 5. A binding-post screw 20 engages the threaded sleeve 18 and when 10 tightened tends to insure snug setting of the flange of the sleeve against the shouldered terminal of the bore 16, as illustrated in dotted line by Figure 1. It is obvious that, by this improved method of assembling these 15 parts of the lamp socket, the portion of metal ordinarily discarded is not only utilized, but certain parts ordinarily used in the construction of an electric lamp socket, such as the separate binding-post of the screw-shell contact and connecting parts are eliminated.

What I claim is:—

1. An electric lamp socket comprising, in part, a body of insulation having indentations in its peripheral surface, each indentation 25 providing a shoulder, and a screw-shell having integral arms, each arm having an off-set terminal for locking engagement with a body shoulder;
2. An electric lamp socket comprising, in part, a body of insulation having indentations in its peripheral surface, each indentation providing a shoulder and both indentations being connected by a bore extending through the body, a screw-shell contact having integral arms, each arm having a bored off-set terminal for locking engagement with a body shoulder, and a screw within the bores and connecting the arms and held by a threaded nut on the end of the screw, the screw- 30 head providing means for binding a circuit wire to an arm of the screw-shell contact;
3. An electric lamp socket comprising, in part, a body of insulation having indentations in its peripheral surface, each indentation 35 providing a shoulder; and a screw-shell contact having integral arms, each arm having an off-set terminal for locking engagement with a body shoulder, one of the arms forming a terminal for the screw-shell contact;
4. An electric lamp socket comprising a body of insulation having indentations in its peripheral surface, each indentation providing a shoulder; a screw-shell contact having 45 arms, each arm having an off-set extremity for locking engagement with a body shoulder, one of the arms forming a terminal for the screw-shell contact; a washer of insulation locked between the shell and the body; and a 50 conductive member mounted upon the washer.

GEORGE HENRY ELWELL.
